UNITED STATES PATENT OFFICE.

ZYGMUNT GADOMSKI, OF JERSEY CITY, NEW JERSEY.

RING HOLDER FOR PENCILS.

Application filed March 25, 1925. Serial No. 18,128.

To all whom it may concern:

Be it known that I, ZYGMUNT GADOMSKI, a citizen of Poland, and resident of Jersey City, in the county of Hudson and State of

5 New Jersey, have invented certain new and useful Ring Holders for Pencils, of which the following is a specification.

This invention relates to improvements in pencil-holders, and more particularly to a 10 novel ring-holder for pencils, and the like, and it is the principal object of the invention to provide a holder adapted to securely hold a pencil in place during its use and to allow a holding of the pencil on the finger 15 when not in use without interference with the other occupations of the fingers of a hand, thus providing a device which does away with the necessity of searching for a mislaid pencil or the like consuming considerable time.

Another object of the invention is the provision of a ring-holder for pencils allowing a convenient adjustment of the ring to any size of finger.

25 A further object of the invention is the provision of a ring-holder for pencils with which a clip is combined for holding pencil and device attached to the pocket of a person, if this is desired.

30 A still further object of the invention is the provision of a holder for pencils having substantially the form of an adjustable ring and one which allows a folding of this ring against the pencil when carried on the person.

35 These and other objects and advantages of my invention will become more fully apparent as the description thereof proceeds, and will then be specifically defined in the appended claims.

40 In the accompanying drawing, forming a material part of this disclosure:

Fig. 1 is a side elevation of my improved ring-holder for pencils and the like on an 45 enlarged scale and attached to the finger of a hand in writing position of the pencil.

Fig. 2 is a side elevation of the ring-holder.

Fig. 3 is an end view thereof.

50 Fig. 4 is a top plan view of my improved pencil-holder.

The holder comprises a split sleeve or socket 10 having upper parallel flanges 11 and 12, and a lower, rearwardly extending 55 bottom element 13 trough-shaped in cross-section and presenting a support for a pencil

14 or the like. The extreme outer end of the element 13 is folded upon itself to form a clip 15 with an outer enlarged and rounded end 16.

60 Between the flanges 11 and 12 a pin 17 is transversely passed through both flanges, and this pin passes also through the lower flanges 18, 19 of a ring generally indicated 65 20, and of a construction more fully to be described hereafter. In this manner the flanges 18, 19 are pivotally held between flanges 11 and 12; they have lower rounded lips 21 and rearwardly extending lips 22. Lips 21 and 22 have comparatively sharp 70 lower edges adapted to engage and cut somewhat into the material of the pencil in either position of the holding device, to hold the pencil to the device when it is used and to hold it in place thereon when not in use.

75 The ring member 20 consists of two bands 23, 24, the outer one, 24 being provided with a segmentally formed slot 25, and a plurality of holes 26, while the inner one, 23, has its free end angularly bent and passed 80 through the slot 25 and formed into a grip 27. The inner ring is also formed with gripping flanges 28 having teeth 29 at their lower faces adapted for engagement into the holes 26 in order to lock the parts in their 85 adjusted position.

The device operates as follows:

A pencil is placed into the trough-shaped bottom element 13 and socket 10, and if now 90 the ring is attached to a finger and moved forward, the sharpened lower edges of its flanges 21 will engage and sink into the wood 95 of the pencil and hold the parts in position. The ring is then adjusted to the size of the finger by the proper operation of handle 27 to depress the inner member and move it with its prongs or teeth 29 into engagement with the openings 26. If the device is not in use, the ring 20 is swung about the pivot point 17 into the position indicated in broken lines in Figure 2, in which the lips 22 will engage the wood of the pencil and hold the same in position in the holder. The clip 15, 16 is used in the ordinary well known manner, if it is desired to carry the pencil 100 like a fountain pen in the pocket while the ring is in the dotted line position, Figure 2.

105 It will be clear that changes may be made in the construction of my ring-holder for pencils and of its minor details without departure 110 from the scope and spirit thereof as defined by the appended claims.

Having thus described my invention, what I claim as new, and desire to secure by Letters Patent is:

1. Ring holder for pencils comprising a socket split to form upstanding flanges, a trough-shaped rearwardly extending body element formed with said socket, and a ring-shaped holder for a pencil pivotally secured between the upstanding flanges of said socket.
2. Ring holder for pencils comprising a split socket, upstanding flanges on said socket, a trough shaped, rearwardly extending member formed with said socket for supporting a pencil, an adjustable finger ring pivotally attached between said upstanding flanges, and means on said ring for engaging the pencil in either position of the ring with respect to the pencil.
3. Ring holder for pencils comprising a socket, flanges connected therewith, a transverse pivot pin, a ring composed of an outer

and an inner member having flanges secured by said pivot pin between said flanges, means for holding the outer and the inner members of said ring in their adjusted relative positions, and a pair of lips on said flanges adapted to engage the pencil in either position of the rings to the pencil.

4. In a ring holder for pencils of the class described comprising a pencil rest and clip, a ring composed of two parts, an outer part having a segmental slot, and a plurality of perforations therein, and an inner part having its end extended through the segmental slot and fingers formed at the edges of said inner part to grip over the outer ring, and teeth formed with said fingers to engage the holes in said outer part, and pencil engaging lips on said ring parts.

Signed at New York in the county of New York and State of New York, this 21st day of March, A. D. 1925.

ZYGMUNT GADOMSKI.
